United States Patent Office

Des. 183,923
Patented Nov. 18, 1958

183,923

CABINET

Naylor C. Foster, Sr., Hendersonville, N. C.

Application October 9, 1956, Serial No. 43,279

Term of patent 3½ years

(Cl. D33—19)

Fig. 1

The design is characterized by the portion of the drawing shown in full solid lines.

I claim:

The ornamental design of a cabinet, substantially as shown and described.
